UNITED STATES PATENT OFFICE.

BENNARD H. POMEROY, OF ROCHESTER, NEW YORK.

TIME SWITCH.

Application filed February 18, 1922. Serial No. 537,623.

To all whom it may concern:

Be it known that I, BENNARD H. POMEROY, a citizen of the United States of America, residing at Rochester, in the county of Monroe and State of New York, have invented certain new and useful Improvements in Time Switches, of which the following is a specification.

The object of this invention is to provide an electrical switch for use in connection with heating devices designed to furnish heat for a limited time only. Such heaters are employed in manifolds and operate to gasify the gasoline and air mixture drawn through the carburetor of an internal combustion engine.

These and other objects of this invention will be fully illustrated in the drawing described in the specification and pointed out in the claims at the end thereof.

In the accompanying drawing:

Figure 1 is a vertical sectional view of the switch as it will appear when attached to the dash board of an automobile.

Figure 2 is a top plan view of the switch.

Figure 3 is a bottom plan view of the switch.

Figure 4 is an end elevation of the switch.

Figure 5 is a vertical sectional view of the switch, the section being taken on the line 5^x—5^x of Figure 2.

Figure 6 is a vertical section of the switch, the section being taken on the line 6^x—6^x of Figure 3.

In the several figures of the drawing like reference numerals indicate like parts.

Electric manifold heaters such as are intended to be controlled by the switch forming the subject matter of this invention comprise a heating coil which is mounted in the manifold of an internal combustion engine so that the gases passing into the intake of the engine are pre-heated and vaporized thereby before entering the cylinders. The coil of these heaters is brought to a high degree of temperature by an electric current which in the case of an automobile is furnished by the storage battery of the lighting or ignition system of the car. As a large amount of current is drawn by the heater from the battery during the time the heater is in use it is imperative that the time during which the heater is in use be limited to the actual time necessary to gasify sufficient fuel

to run the engine until the heat of the engine

itself will operate to gasify the fuel without the use of the heater. This is needed to avoid waste of current and protect the battery against exhaustion.

This time limit may be set for a minute or 60 a fraction of a minute depending on the climate and to a certain extent the type of engine.

The switch proper comprises the face plate 1 in which the push button 2 is mounted. 65 To provide a limited movement for the push button 2 in the face plate 1 the face plate is bulged out in the middle to form a clearance 3 between the face plate. A collar 5 is formed at the rear of the push button to 70 limit the movement thereof in either direction by making contact with face plate at one end and with the backing plate at the other end of its movement.

The push button is provided with an extension 6 of reduced diameter which extends rearwardly through an opening in the backing plate into the sleeve 7 formed integral with the backing plate or suitably fastened thereto. The front half of the sleeve as well 75 as the opening in the backing plate has an inside diameter which is slightly larger than the outside diameter of the extension 6 of the push button. Placed into the clearance formed in the sleeve 7 in this manner is the 80 expansion spring 8 which encircles the extension 6 of the push button and is held in place between the rear of the collar 5 and the shoulder 9 formed at the end of the enlarged section of the sleeve. The spring 8 normally 85 forces the push button outwardly into the full line position illustrated in Figure 1.

Mounted on the outer end of the sleeve 7 is a disk or plate 10. On this plate are carried the posts 11 and 12 which project rearwardly therefrom preferably at diagonal points from each other. These posts support a second disk or plate 13 at a suitable distance from the first plate 10. While the first plate is made of metal and forms a good 90 conductor of electricity the second plate 13 is made of insulating material such as fiber and forms the switch board proper.

The switch mounted on the insulating disk 13 is a knife switch and comprises the 105 blade 14 and the clip 15. The blade 14 is pivotally mounted on the lug 16 near the bottom of the insulating disk and the clip 15 is mounted near the top of the same disk. A spring 17 is held in place on the lug 16 and 110

the free end thereof is wound around the lower end of the knife blade 14 and normally holds the upper end thereof out of engagement with the clip 15. In doing so the rear 5 of the blade 14 is forced against the opening in the front of the plate 10 forming a continuation of the sleeve 7. The end of the extension 6 of the push button 2 is adapted to move out of this opening in the plate when 10 the push button is operated and makes contact with and swings the blade 14 into engagement with the clip 15. The frictional contact which the end of the blade makes with the clip is sufficient to hold the blade 15 in engagement with the clip against the force of the action of the spring 17, so that on the release of the push button by the operator the knife switch remains closed while the 20 push button is forced back from the dotted line position which the push button occupies when operating the switch as above pointed out to the full line or normal position. This is automatically done by the action of the expansion spring 8 on the release of the push 25 button.

The electric current passes through the switch when closed as follows. It enters through the wire marked 18 which is suitably connected to the clip 15. From the clip 30 the current passes through the knife blade 14 to the lug 16 on which the blade is mounted to swing. This lug in turn is connected to the heating coil 20 wound around a portion of the thermometal spring 21. The 35 wire in this heating coil is copper and is preferably uninsulated. From this coil the current passes to one of the posts 11 or 12 from either one of which it passes to the heater in the manifold such as is described in 40 my prior application 390,625 filed June 21, 1920, which is controlled by the operation of the switch.

The thermometal spring is mounted with one end thereof to the under side of the 45 sleeve 7 near the backing plate thereof and its outer end is left to project into the path of the lug 22 formed on the rear of the blade 14 of the switch proper. While the switch is open and no current passes therethrough 50 following the path outlined above the lug 22 on the blade is located slightly below the outer end of the thermometal spring and does not make contact with it. When the switch is closed the lug 22 is forced against 55 the under side of the thermometal spring 21 and slightly raises the outer end thereof while it makes contact therewith. As soon as the circuit is closed the electric current passes through the heating coil 20 following 60 the path above pointed out and heats the coil 20 and in turn the thermometal spring 21.

Thermometal which is used in making the spring 21 is made up of two metals each 65 having a different coefficient of expansion,

as for instance steel and brass. The different metals are rolled together in sheet form so as to closely adhere together and practically form but one sheet of metal. The metal built up in this manner is sensitive to 70 temperature and curves when heat or cold is applied to it. This is due to the fact that the one metal on one side of the sheet expands more than the metal on the other side of the sheet, with the consequence that the 75 metal having the greater expansion must expand by curving around the metal having the smaller expansion, as neither one can separate itself from the other to expand in a straight line independently. 80

When, therefore, the thermometal spring 21 employed in this switch is heated by the heating coil 20 the outer end thereof curves during its expansion and this action of the thermometal spring operates to force down 85 on the lug 22 and pull the knife blade 14 out of engagement with the clip 15. The electric circuit is thus automatically broken by the expansion of the thermometal spring 90 caused by the application of heat through the electric current which passes through the switch.

The knife blade 14 has a vertical groove 95 23 cut into one side thereof near the outer end of the blade. The clip 15 has an inwardly projecting ridge 24 formed near the outer end of one of the jaws of the clip on the same side on which the groove 23 is provided in the knife blade. The ridge 24 of the clip 15 is adapted to make frictional contact with the side of the knife blade on which the groove 23 is formed and to enter this groove to hold the knife blade in engagement with the clip to close the electric 100 circuit. 105

The distance between the jaws of the clip 15 is so adjusted that when the knife blade enters between them to close the electric circuit it is held yieldingly in frictional engagement between them by reason of the engagement of the ridge 24 with the groove 23. The amount of pressure needed to pull the knife blade out of engagement with the clip determines the time that it takes the thermometal spring to perform this operation. 110 This is regulated by increasing or decreasing the distance between the jaws of the clip 15 so that the knife blade is held in the clip with stronger or weaker grip, which in turn allows the thermometal spring to pull the knife blade out of engagement with the clip in a longer or shorter period from the time the switch is closed to close the electric circuit. 115 120

The manifold heating coil in connection 125 with which the switch is used is heated before the engine starts and being located in the manifold it heats the mixture in the manifold so that when the engine is cranked it will on its first turn draw a hot charge 130

into the engine which is easily fired and starts the cycle of the engine. The application of the current to the coil for thirty to sixty seconds before starting the engine is 5 usually sufficient on a cold morning to secure this result, and the switch shown in the drawing is set to operate to break the circuit in this length of time after the circuit has been closed by operating the push 10 button.

The face plate may be conveniently fastened to the dashboard of an automobile at a point where the operator of the car can readily reach the push button.

15 For the purpose of manually breaking the switch in the event that the thermometal spring fails to perform its function, a dog 25 is provided on the end of the extension of the push button. This dog is fastened to 20 one side of the end of the extension and normally does not make contact with the knife blade during its forward and rearward movement with the push button. Should the knife blade fail to disengage itself from 25 the clip, the push button, with the help of the dog 25, can be used to open the switch. For this purpose the push button is pushed in until the end of its extension is brought into contact with the back of the knife blade 30 14. The push button is then turned until the hook shaped end of the dog engages the front of the knife blade, as illustrated in Fig. 6. When this is done the push button is released and the expansion of the spring 8 35 brings the push button back to its normal position. In doing so the knife blade which has been hooked by the dog 25 is pulled back with the push button and out of engagement with the clip 15. When the 40 switch has been opened in this way the push button may be turned back to its normal position to disengage the dog 25 from the knife blade, so that on the next operation of the push button the switch does not open 45 when the button is released by the operator.

This invention is described in connection with a heating coil but it will be understood that it can be used effectively for many other purposes as well.

50 I claim:

1. In a thermostatically controlled time switch the combination of a push button, a knife switch, said push button being adapted to close said knife switch, a thermometal 55 spring adapted to open said knife switch and a heating coil surrounding said thermometal spring and electrically connected in series with said knife switch and means for opening said knife switch independently of 60 said thermometal spring.

2. In a thermostatically controlled time switch, the combination of a push button, a sleeve surrounding said push button, a plate supported on the end of said sleeve, a pair 65 of posts projecting rearwardly from said

plate, an insulating panel supported by said posts, a knife switch mounted on said insulating panel, a thermometal spring mounted on said sleeve, said push button being adapted to close said switch and said 70 thermometal spring being adapted to open said knife switch.

3. In a thermostatically controlled time switch, the combination of a sleeve, a push button mounted to slide in said sleeve, an 75 insulating plate supported by said sleeve, a clip mounted on said plate, a knife blade mounted on said plate diametrically opposite to said clip, said push button being adapted to engage the rear of said knife 80 blade and operate to move said blade into engagement with said clip, a thermometal spring adapted to pull said knife blade out of engagement with said clip, a heating coil electrically connected in series with said 85 knife blade to raise the temperature of said thermometal spring and pull the knife blade out of engagement with said clip to break the electric circuit formed by said knife switch on the operation of said push 90 button.

4. In a thermostatically controlled time switch, the combination of a sleeve, a push button mounted to slide in said sleeve, a knife switch comprising a knife blade 95 mounted to swing on the end of said sleeve, a clip adapted to receive the end of said knife blade, said push button adapted to engage said knife blade and force it into engagement with said clip, a thermometal 100 spring, a lug projecting rearwardly on said knife blade, said thermometal spring being adapted to engage said lug when said switch is closed and pull said knife blade out of 105 said clip to open the circuit.

5. In a thermostatically controlled electric switch the combination of a knife switch, comprising a knife blade and a clip, a thermometal spring operating on said knife blade to open the knife switch at a predetermined period after closing the switch, manual means operating to close said switch and means carried on said manually operated means to either leave the knife blade in engagement with the clip or withdraw therefrom on the release of said manually operated means.

6. In a thermostatically controlled electric switch the combination of a knife switch comprising a knife blade and a clip, a thermometal spring operating on said knife blade to open the knife switch at a predetermined period after closing the switch, a push button operating to close said switch, a dog 120 carried on said push button and moving back and forth and turning sideways therewith, said dog when turned to one position being adapted to engage the knife blade to open the switch on the backward movement of said button, and when in normal angular 125 130

position being adapted to leave the switch closed on the backward movement of said button.

7. In a thermostatically controlled switch the combination of a knife switch comprising a knife blade and a clip into which said knife blade engages, a push button adapted to engage the rear of said knife blade and to force said knife blade in engagement with said clip on the forward movement thereof,

a dog carried on the end of said push button, said dog being adapted to pass by said knife blade during its forward motion, said dog being adapted to engage in front of said knife blade on the rotation of said push button and pull the knife blade out of engagement with said clip on the rearward motion thereof. 15

In testimony whereof I affix my signature.

BENNARD H. POMEROY.
